CLAIM

The ornamental design for a horticulture lighting controller chassis, as shown and described.

DESCRIPTION

FIG. 1 is a perspective view of a first embodiment of a horticulture lighting controller chassis, as viewed from the front, showing our new design;

FIG. 2 is a perspective view of the chassis shown in FIG. 1, as viewed from the rear;

FIG. 3 is a right side view of the chassis shown in FIG. 1;

FIG. 4 is a left side view of the chassis shown in FIG. 1;

FIG. 5 is a top elevation view of the chassis shown in FIG. 1;

FIG. 6 is a bottom elevation view of the chassis shown in FIG. 1;

FIG. 7 is a front plan view of the chassis shown in FIG. 1;

FIG. 8 is a rear plan view of the chassis shown in FIG. 1;

FIG. 9 is an exploded perspective view of a second embodiment of a horticulture lighting controller chassis, as viewed from the front, showing our new design, the second embodiment comprising a kit of three separate components, a front component shown in FIGS. 17-23, a top component shown in FIGS. 24-30, and a rear or backplane component shown in FIGS. 10-16;

FIG. 10 is a perspective view of a rear component of the chassis shown in FIG. 9, as viewed from the front;
FIG. 11 is a right side view of the rear component shown in FIG. 10;
FIG. 12 is a left side view of the rear component shown in FIG. 10;
FIG. 13 is a top elevation view of the rear component shown in FIG. 10;
FIG. 14 is a bottom elevation view of the rear component shown in FIG. 10;
FIG. 15 is a front plan view of the rear component shown in FIG. 10;
FIG. 16 is a rear plan view of the rear component shown in FIG. 10;
FIG. 17 is a perspective view of a front component of the chassis shown in FIG. 9, as viewed from the front;
FIG. 18 is a right side view of the front component shown in FIG. 17;
FIG. 19 is a left side view of the front component shown in FIG. 17;
FIG. 20 is a top elevation view of the front component shown in FIG. 17;
FIG. 21 is a bottom elevation view of the front component shown in FIG. 17;

FIG. 22 is a front plan view of the front component shown in FIG. 17;
FIG. 23 is a rear plan view of the front component shown in FIG. 17;
FIG. 24 is a perspective view of a top component of the chassis shown in FIG. 9, as viewed from the front;
FIG. 25 is a right side view of the top component shown in FIG. 24;
FIG. 26 is a left side view of the top component shown in FIG. 24;
FIG. 27 is a top elevation view of the top component shown in FIG. 24;
FIG. 28 is a bottom elevation view of the top component shown in FIG. 24;
FIG. 29 is a front plan view of the top component shown in FIG. 24; and,
FIG. 30 is a rear plan view of the top component shown in FIG. 24.
The broken-line disclosure shown in the views is understood to represent portions of the article in which the claimed design is embodied, but which form no part of the claimed design.
